UNITED STATES PATENT OFFICE

170,084

LIGHTING FIXTURE

George E. Glatthar, University Heights, and Arthur W. Matteson, Lakewood, Ohio, assignors to The Art Metal Company, Cleveland, Ohio, a corporation of Ohio

Application December 5, 1952, Serial No. 22,573

Term of patent 14 years

(Cl. D48—23)

To all whom it may concern:

Be it known that we, George E. Glatthar and Arthur W. Matteson, citizens of the United States and residents, respectively, of University Heights, Cuyahoga County, Ohio, and Lakewood, Cuyahoga County, Ohio, have invented a new, original, and ornamental Design for a Lighting Fixture, of which the following is a specification, reference being had to the accompanying drawing, forming a part hereof.

The single drawing figure is a perspective view of a lighting fixture, showing our new design.

We claim:

The ornamental design for a lighting fixture, as shown.

GEORGE E. GLATTHAR.
ARTHUR W. MATTESON.
